UNITED STATES PATENT OFFICE.

LEON CAMETO, OF OAKLAND, CALIFORNIA, ASSIGNOR TO MODERN FOUNDRY AND PATTERN WORKS, OF OAKLAND, CALIFORNIA, A CORPORATION OF CALIFORNIA.

CLOTHES WRINGER.

Application filed December 23, 1925. Serial No. 77,837.

My invention relates to clothes wringers, and it has particular reference to such clothes wringers as are adapted to be attached to the wringer-drive mechanism of washing machines.

If, during the operation of wringers of this kind that I am aware of, a person should accidentally get his fingers caught between the rollers and, in his efforts to free himself, he strikes the roller release means of the wringer, should it have any, the rollers will separate apart only a short distance and will continue to draw the fingers therebetween so that the whole hand and even a part of the arm may follow before the wringer is stopped. Then, before the person can be released from the wringer, the drive mechanism must be reversed so that the parts already pinched will be again subjected to the torture, but with diminishing pressure.

Also, in order to separate the rollers from each other in wringers of this kind, it has heretofore been necessary to relieve the pressure on the upper roller, as otherwise, when the rollers are suddenly released from each other, loose parts are liable to be violently ejected from the wringer frame by the spring reaction, so that serious injury may often be occasioned when the wringer is left to the care of an inexperienced person.

The principal object of this invention is to provide a clothes wringer in which the rollers are contained in separate housings adapted to be clamped together as a unit and so arranged that they can be instantaneously and completely separated from each other, and thus prevent any further injury to a person's fingers or hand that have accidentally been caught between the rollers during the operation of the wringer.

Another object of the invention is to arrange the driving and the driven gears of the rollers at the end opposite to the wringer's connection with the drive mechanism so that when the housings are released by the safety means, the upper roller will be immediately released from its gear connection with the lower roller that carries the drive gear.

A further object of the invention is to retain in its housing, when the housings are separated, the roller having the spring tension thereon without necessitating releasing

the applied tension on the roller as heretofore done.

A still further object of the invention is to provide the demountable section of the wringer with stop means so that, when it becomes necessary to operate the safety release, the reaction of the sudden release of the stressed wringer will be absolutely nil, in contrast to the violent movement and ejection of parts of other wringers as heretofore have been known.

A still further object is to provide that not only shall the upper housing and its roller be entirely removable as a unit as the ideal safety feature, but that the lower roller shall also be entirely removable from its housing for accessibility, inspection, repair and cleaning purposes.

In addition to the above broader features of the invention, there are certain details of design, whereby compactness, durability of structure, and positiveness and ease of operation are attained, and which details are shown on the accompanying three sheets of drawings illustrating the present embodiment of my invention, and what I claim as new, is particularly pointed out in the appended claims following this specification.

Referring to the drawings:

Figure 1 is a plan of my improved clothes wringer.

Fig. 2 is a front elevation of it and shown attached to a washing machine wringer mechanism, the latter being partly in section. Also, part of the wringer is shown in section to show the normal position of the wringer-rolls and the drive therefor.

Fig. 3 is a central transverse section of the wringer.

Fig. 4 is a central longitudinal section through the housing to show the rolls in service, and in particular the relation between the upper roll spaced from the stop pins and tensioned against the spring.

Fig. 5 is a view similar to Fig. 4 but showing that the safety handle has been released, and that the compression of the clothes immediately has reacted and caused the upper half of the wringer to assume the at-rest or no-pressure position shown; the roller hubs resting on the stop pins again by the reaction of the spring.

Fig. 6 is an outline view primarily to show that the upper housing including its roll

can be quickly and easily detached from the lower housing.

Fig. 7 is an enlarged view, and partly in section, of the coupling end of the lower housing with that of the wringer drive of Fig. 2. It is here shown that the lower roll, by tilting, can be easily withdrawn from its drive member.

Fig. 8 is a transverse section along the line 8—8 of Fig. 7; and

Fig. 9 is a plan of the bottom housing, and in dotted lines is the tiltable drain board.

In the drawings the wringer of my invention is indicated as a whole by the numeral 10. This wringer 10 comprises an upper housing 11 and a lower housing 12, both of which housings preferably are made of an aluminum alloy. The upper housing has thereon at one end a hook-shaped hinge 13 Figs. 4 and 5, which is adapted to hook under a pin 14 driven through openings in ears 15 on the inner side of a flange 16 at one end of the lower housing 12. Hooks 17, integral with the casing 18 of a wringer-drive mechanism 19 Fig. 2, of a washing machine, not shown, and bolt and nut means 20 serve the purpose as a means of securely holding my wringer to a washing machine.

At the end opposite to the hook-shaped hinge 13 the upper housing 11 has integral therewith a lug in the form of a hook 21 Fig. 5, and the lower housing 12 has integral therewith a projection 22, in which is pivotally secured, as indicated at 23, the inner ends of two links 24. The outer ends of the links are in their turn pivotally secured, as indicated at 25, to a clamping member 26 provided with a curved handle 27 and with a tongue portion 28 adapted to engage with the hook 21 for holding the housings 11 and 12 locked together as a unit when the hinge 13 also engages the pin 14, as is best shown in Figs. 1, 2 and 4. In Figs. 2 and 4 it is also shown that the handle 27 extends above the upper housing 11, and is within a convenient reach of the hands of an operator, so that in emergency an outward push on the handle would release the engagement of the tongue portion 28 with the hook 21 and render the upper housing 11 instantly removable from the lower housing 12.

In roller bearings 29 Fig. 4, which are slidably secured in guides 30 Fig. 9 integral with the lower housing 12, is mounted a shaft 32, upon which is secured a roller 33, between the bearings, and the shaft 32 extends outside of the flange 16 and is adapted to enter into the bored hub 34 Fig. 7, of the wringer-drive gear 35. The shaft has a pin 36 driven therethrough to engage the side walls of a recess 37 in the hub, so that the drive mechanism 19 can thereby communicate motion to the shaft 32 and the roller 33 secured thereto. At its outer end, relative to

the drive mechanism 19, the shaft 32 has secured thereto a double drive-gear 38.

In roller bearings 39 which are slidably secured in guides 40 integral with the upper housing 11 is mounted a shaft 42, which has secured thereupon between the bearings a roller 43 and at its outer end, relative to the drive mechanism 19, a double gear 44 adapted to be driven by the gear 38 when the housings 11 and 12 are clamped together, as is best shown in Figs. 2 and 4. The guides 30 in the lower housing serve the purpose of holding the bearings 29 in such a position on the shaft 32 that only a slight end play of the shaft is allowed in order to assure a free and easy running of the shaft in the lower housing, and the guides 40 serve a similar purpose for the shaft 42 in the upper housing and are further so arranged that the gears 38 and 44 mesh perfectly when the housings are united.

A stiff flat spring 45 is mounted in the upper housing and is adapted, adjacent to its ends, to press upon blocks 46, which are provided with grooved ends for engagement with the grooved guides, and the spring may be provided with downward turned ends as a means for preventing the spring from sliding out of engagement with the blocks. A member 47 Fig. 3, embracing the spring 45 approximately at the midway portion thereof so as to be fixed thereto, is at its top preferably provided with a conical opening 48 for receiving therein the frusto-conical end of a tension-regulating screw 49, which has thereon at its upper end a hand wheel 50 for facilitating its turning and extends in screw-threaded engagement through a boss 51 on a plate 52, and the boss extends through an opening in the top of the upper housing while the plate is secured to the inside of the housing by screws 53 or by any other suitable means, so that the screw 49, when engaging the opening in the member 47, will thus hold the spring 45 in a virtually central relation over the roller 43 both longitudinally and transversely in the upper housing.

Under the shaft 42 and near one end thereof the housing 11 has therein a pin 54, which is driven through the side walls of the housing and bridges the opening of the housing, and under the shaft at its opposite end another pin 55 is similarly driven through the side walls of the housing so as to bridge the opening of the housing between the gear 44 and the roller bearing 39 beside it, so that the pins 54 and 55 thus retain the shaft 42 with its roller 43 in the housing against the tension of the springs 45 when the housings 11 and 12 are released from each other at one end, as shown in Fig. 5, or even when they are entirely free from each other at both ends.

The wringer 10 has on each side of the lower housing a clothes board 56 provided on its upper side and at each of its ends with a

rib 57, and the clothes board is spaced at its inner edges 58 from the roller 33, as shown in Figs. 3 and 9, so that, when the wringer is in use, the water wrung out of the washed articles will flow down between the roller and the clothes board and will not be liable to follow them to the outer edge of the clothes board.

Under the lower housing is a drain board 59, which has at each end an upward extending lug 60, and the lower housing has corresponding downward extending ears 61, to which the respective lugs 60 are pivotally secured, so that the drain board may be tilted toward or away from either of the clothes boards 56, which overlap the drain board. The drain board is also provided at its ends with upward extending ridges 62, so that the water flowing down through the spaces between the inner ridges 58 of the clothes boards and the roller 33 will be caused to run back into the washing machine to which the wringer-drive mechanism 19 is attached, or to run down into any other receptacle, according to the position upon which the wringer is swung upon the vertical shaft of the wringer-drive mechanism and according to how the drain board is tilted.

In operation, when the wringer 10 has been connected with the drive mechanism 19 of a washing machine, and when the housings 11 and 12 have been clamped together and the tension of the spring 45 upon the blocks 46 has been adjusted by the screw 49, a washed article 63, passing from one of the clothes boards 56, will be drawn between the rollers 33 and 43 and will cause the roller 43 to rise against the tension of the spring, as shown in Fig. 4, so that the water will be squeezed out of the article and will flow, as before explained, through the spaces between the lower roller 33 and the inner edges 58 of the clothes boards down onto the drain board 59.

If during the wringer operation the operator accidentally should get the fingers of one hand caught between the rollers, the operator can instantly extricate himself with his other hand from his predicament by pushing the releasing handle 27. In fact, the handle of the safety clamp is in such a position that impulsively the operator's hand is naturally guided to follow the top of the housing 11 to the handle, so that the release of the clamping device is almost automatic. When the safety clamp has thus been released the expansion of the compressed article 63, or hand, will cause the outer end of the housing 11 to be raised out of contact with the lower housing, as shown in Fig. 5, thus disengaging also the gear 44 from the gear 38 so that no power is applied to the upper roller 43 and therefore the hitherto compressed article or im-

prisoned hand readily can be withdrawn. Simultaneously with the reaction of the compressed article the tension of the spring 45 will react and force the roller shaft 42 toward the stop pins 54 and 55, thus dissipating the reactive force so that its effect is nil and accomplishing it in the time interval that it takes the upper roller to travel a downward distance equal to the distance between the pins and the shaft 75 mountings.

In order to resume the operation of the wringer, it is only necessary to reclamp the upper housing to the lower housing by means of the clamping device, as has been explained, and without readjusting the tension of the spring 45, since the tension will remain the same as before the housings were separated, if the adjustment of the screw 49 has not been changed.

As shown in Fig. 2, the pins 54 and 55 are so located that the upper roller is pressed upon the lower roller when no article is between the rollers and when the housings are clamped together. In this instance, the links 24 are swung past the perpendicular toward the upper housing. Thus, it is obvious that, when the housings are clamped together, the rollers in pressure engagement sufficient for producing an initial pressure due to the resiliency of the rollers before the upper roller 43 on its shaft 42 is moved upward from its at-rest position on the pins 54 and 55 by other than thin articles passed between the rollers. This initial pressure is sufficient to allow an article, such as a handkerchief, to be carried between the rollers and thereby have the water squeezed therefrom without the upper roller moving from its at-rest position, so that therefore the wringer is always available for thin as well as thick articles.

It should be observed that, when the clamping engagement of the housings is quickly released and the upper housing in consequence will spring upward, as shown in Fig. 5, no injury can follow from such upward springing movement, since the parts in the upper housing are retained therewithin by the pins 54 and 55. The housings, of course, when it is so desired, may be entirely unhooked from each other, as shown in Fig. 6, and, when the housings are out of engagement with each other, the roller 33 may be removed from the lower housing simply by first lifting the geared end of the roller shaft 32 above the top of the housing. The shaft with the roller thus tilted, as shown in Fig. 7, may then easily be withdrawn from engagement with the wringer-drive mechanism 19 and subsequently lifted out of the housing 12. When the housing 12 is not connected with a wringer-drive mechanism, the roller 33 may be lifted directly out of the housing without tilting. The easy removal 130

1
of the roller in either case facilitates the cleaning of the housing as well as the drain board thereunder.

From the foregoing description taken in connection with the accompanying drawings, the advantages of the construction and method of operation will be readily understood by those skilled in the art to which the invention appertains, and while I have described 10 the principle of operation, together with the device which I now consider to be the best embodiment thereof, I desire to have it understood that the device shown is merely illustrative and that such changes may be 15 made, when desired, as fall within the scope of the appended claims.

Having thus described my invention, what I claim as new and desire to secure by Letters Patent of the United States, is the 20 following:

1. A clothes wringer comprising an upper and a lower housing, a roller secured to a shaft rotatably mounted in each housing, the upper housing being hooked to the lower 25 housing at one end thereof so that the upper housing can swing in the plane of the roller shafts and also be entirely removed from the lower housing, a hook member upon the other end of the upper housing opposite to 30 the end where the upper housing is hinged, a linked clamping member carried by the lower housing in juxtaposition to said hook, a cam member upon said clamping member

adapted to connect with said hook in order to normally clamp the upper and lower housings together and means whereby said rollers may be operated in unison when in normal position. 35

2. A clothes wringer comprising an upper and a lower housing, a roller secured to a shaft rotatably mounted in each housing, the upper housing being hooked to the lower housing at one end thereof so that the upper housing can swing in the plane of the roller shafts and also be entirely removed from the lower housing, a hook member upon the other end of the upper housing opposite to the end where the upper housing is hinged, a linked clamping member carried by the lower housing in juxtaposition to said hook, a cam member upon said clamping member adapted to connect with said hook in order to normally clamp the upper and lower housings together, means whereby said rollers may be operated in unison when in normal 40 position, spring means in the upper housing urging the roller therein outwardly and fixed stop pins extending between the side walls of the upper housing under the shaft of the roller therein adapted to limit the downward 45 movement of said roller so that when the housings are clamped together a slight initial pressure is produced on the rollers. 50

In testimony whereof, I affix my signature.

LEON CAMETO.
